Application January 7, 1959, Serial No. 54,059

Term of patent 14 years

(Cl. D34—15)

FIG. 1

Fig. 2 is an end plan of the same taken from the left-hand side of Fig. 1, with a portion shown fragmentarily for convenience of illustration.

Fig. 3 is a bottom plan view thereof.

The dominant features of the design reside in the portions shown in full lines.

I claim:

The ornamental design for a hobby horse stand, as shown and described.
